(57) **CLAIM**

The ornamental design for a facemask front clip, as shown and described.

DESCRIPTION

FIG. 1 is a top front perspective view of the invention.

FIG. 2 is a top view of the invention.

FIG. 3 is a bottom view of the invention.

FIG. 4 is a side view of the invention.

FIG. 5 is an opposing side view of the invention.

FIG. 6 is a front view of the invention.

FIG. 7 is a perspective view of the invention shown in an environment of use; and,

FIG. 8 is a back view of the invention assembled with a corresponding unclaimed facemask assembly.

The broken line depiction of user's head in FIG. 7 shows environmental subject matter that forms no part of the claimed design.

All other broken lines in the drawings depict portions of a facemask front clip that form no part of the claimed design.

1 Claim, 6 Drawing Sheets
